United States Patent Office

Des. 186,351
Patented Oct. 13, 1959

186,351

FACIAL MASK

Paul Meminger, Alhambra, Calif., assignor to Dermaculture, Inc., Beverly Hills, Calif., a corporation of California

Application February 17, 1959, Serial No. 54,641

Term of patent 14 years

(Cl. D86—10)

The essential feature of the design reside in the portions shown in solid lines on the drawing.

I claim:

The ornamental design for a facial mask, as shown and described.
